Patented Nov. 14, 1922:

INVENTOR
ALBERT H. HEINBACH
BY C. E. Enoch, Esq.
ATTORNEY

UNITED STATES PATENT OFFICE.

ALBERT H. HEIMBACH, OF ST. PAUL, MINNESOTA.

INCINERATOR.

Application filed July 31, 1920. Serial No. 400,369.

To all whom it may concern:

Be it known that I, ALBERT H. HEIMBACH, a citizen of the United States, and a resident of St. Paul, in the county of Ramsey and State of Minnesota, have invented certain new and useful Improvements in Incinerators, of which the following is a specification.

One object of my invention is to provide 10 in an incinerator an improved construction of incinerating chamber.

Another object is to provide an improved construction of auxiliary air inlet.

With these and incidental objects in view, 15 the invention consists of certain novel features of construction and combination of parts, the essential elements of which are hereinafter described with reference to the drawings which accompany and form a part 20 of this specification.

In the drawings, Figure 1 is a front view of my improved incinerator; Figure 2 is a section taken on the line 2—2, Figure 1; Figure 3 is a section taken on the line 3—3, 25 Figure 2; and Figure 4 is a section taken on the line 4—4, Figure 3.

As shown in Figures 1 and 3, my incinerator consists of an incinerating chamber 1, enclosed by walls 2, and having the top 30 thereof brought in as at 3 to the chimney flue 4, which extends upwardly through the floor 5 and through as many stories as desired up to and through the roof 6, Figure 2, terminating in the chimney 7.

At each floor a chute 8 is provided having 35 a suitable closure 9.

At the bottom the incinerator chamber is brought in on four sides, as at 10, Figure 3, and a grate 11 is provided, partitioning 40 the incinerating chamber proper from the ash pit 12.

As shown in Figure 4, the grate consists of two grate bars 13 and 14, journaled at 45 15, 16 and 17, 18, respectively. The outer ends 19 and 20 of the grate bars are squared off or otherwise suitably fashioned to receive thereon a lever 21, for shaking the grate.

A suitable door 22 is provided to give 50 access to the incinerating chamber, and an ash door 23 gives access to the ash pit below the grates.

In the constricted portion of the incinerating chamber at 3, Figure 3, is a thimble 55 24 closed by a grid 24', and set into the wall,

and this thimble is used to connect a furnace 26 to the incinerating chamber by pipe 25.

The heater 27 is connected by the pipe 28 to the constricted portion of the incinerating chamber at 29, and a pipe 30 leads from the 60 pipe 28 to a point 31 where it enters the incinerating chamber below the grate.

Dampers 32 and 33 are provided for controlling the draft through the pipes 28 and 30, respectively. 65

A grid 34, Figure 2, is set into the masonry near the top of the chimney 7 to prevent burning material from passing out of the chimney.

The grid or screen 34 prevents burning 70 paper from flying out of the chimney while the grid 24' prevents paper or garbage, dropped into the stack through the chute 8, from getting into and plugging up a thimble 24, and for this reason, it will be 75 noted that the grid 24' is at the inner end of said thimble.

The importance of the arrangement of pipes 28 and 30 and dampers 32 and 33, above described and illustrated in the drawings, should be particularly noted. In starting a fire in the relatively small heater 27, damper 32 will be opened and damper 33 will be closed, thereby giving the desired 80 strong draft into the chimney at a point 85 above the garbage contained on the grate 11, but after the fire has been well started in said heater 27, damper 32 will be closed and damper 33 opened, so that then the hot gases from said heater will be carried 90 into the incinerator chamber at a point below the grate and will be caused to be passed upward through the garbage and rapidly dry the same.

The above arrangement of smoke pipes 95 and independently operating dampers is, therefore, important.

The dimensions of the incinerating chamber, constricted throat, and grate area are proportioned to meet the requirements of 100 the capacity of the building in which the incinerator is installed.

While I have described my invention and illustrated it in several particular designs, I do not wish it understood that I limit myself to this construction, as it is evident that the application of the invention may be varied in many ways within the scope of the following claim.

The garbage on the grate of the inciner- 110

ator will customarily contain a large amount of paper so that the commingled mass, when dry, may be ignited and will burn readily in the incinerator. It is, however, of the utmost importance that the garbage be thoroughly dry and this, as stated, is made possible by adjustment of the dampers 32 and 33 so as to cause the heat products of combustion from the small heater 27 to pass upward through the garbage on the grate of the incinerator. The best garbage burning action will be produced when both the main heater 26 and the auxiliary or hot water heater 27 are in action and the products of combustion from the latter are caused to pass upward through the garbage. Under these conditions the main heater will produce a very strong draft in the flue and the heat products of combustion from the auxiliary heater will not only continue the drying action of the

garbage but will insure a complete combustion of the garbage. The general arrangement of the main and auxiliary heaters and the dampers in the branch pipes of the latter is highly important.

Claim:

The combination with a flue and an incinerating chamber at the base thereof, said incinerating chamber having a grate, of a main heater having a smoke pipe connected to said flue above the grate of said incinerator, and an auxiliary heater having a smoke pipe with two branches, one branch being connected to said flue above the grate of the incinerator and the other branch thereof being connected to the incinerator chamber below the grate thereof, said two branch pipes having independently operative dampers for the purposes set forth. 40

ALBERT H. HEIMBACH.
